UNITED STATES PATENT OFFICE.

HENRY ROMAN, OF BAY POINT, CALIFORNIA, ASSIGNOR TO YATES-AMERICAN MACHINE COMPANY, OF BELOIT, WISCONSIN, A CORPORATION OF DELAWARE.

CHIP BREAKER.

Application filed May 19, 1927. Serial No. 192,525.

The present invention has to do with wood working machines, and is particularly concerned with the manner in which the chip breakers associated with the cutter heads of such machines are held yieldingly against the work.

The purpose of the invention is to provide a novel air snubber which will hold a chip breaker yieldingly but firmly against the work without rebound or chatter, regardless of any variations occurring in the position of the chip breaker by reason of changes in the dimensions of the work.

While the foregoing statement is indicative in a general way of the nature of the invention, other objects and advantages will be apparent to those skilled in the art upon a full understanding of the construction, arrangement and operation of the snubber.

20 In order that the invention may be readily understood, one form of the same is presented herein. It will be appreciated, however, that the invention is susceptible of embodiment in various other forms.

25 In the accompanying drawing a chip breaker is shown equipped with the snubber of the invention.

The chip breaker 10 is pivoted at 11 to a matcher plate 12 in which a suitably driven cutter head is adapted to be journaled, and the plate 12 is slidably mounted on two parallel rails 13, whereby to permit the cutter head and chip breaker to be shifted as a unit toward or away from the longitudinal axis 30 of the associated wood working machine. The chip breaker is held against the work, or, in the absence of any work, against a suitable stop on the matcher plate, by a resiliently yieldable air snubber 14.

40 The snubber 14 includes a cylinder 15 which is pivoted at 16 to the matcher plate, and a hollow piston 17 which is positioned in the cylinder and is provided with a stem 18 which is pivotally associated at 19 with the chip breaker through a quick release device 20.

The space within the cylinder confined by the piston constitutes a compressible air

chamber, and such chamber is connected with a source 21 of air under pressure by 50 means of a flexible conduit 22, whereby to maintain the chamber at all times under pressure.

A spring-pressed ball check valve 23 is positioned in the opening leading from the conduit 22 to the chamber, and serves to close off the conduit when the piston is forced into the cylinder by the chip breaker in yielding, thus causing the air entrapped within the cylinder to function as an air 55 cushion.

The snubber above described constitutes a very efficient yielding support for the chip breaker, and has none of the disadvantages which so often characterize the spring devices used for the same general purpose.

I claim:

1. The combination with a movable chip breaker, of a snubber for the same having a compressible air chamber which is adapted 70 to be connected with a source of air under pressure.

2. The combination with a movable chip breaker, of a snubber for the same having a compressible air chamber, a port in said chamber adapted to be connected with a source of air under pressure, and a one-way valve in said port for preventing air from flowing from said chamber back to said source when the chamber is compressed. 75

3. The combination with a matcher plate and a chip breaker pivotally mounted thereon, of a snubber connecting the matcher plate and the chip breaker and comprising a hollow cylinder connected to one of said members, a piston in the cylinder connected to the other of said members, a port in the cylinder adapted to be connected with a source of air under pressure, and a one-way valve in the port for preventing air from flowing from said chamber back to said source when the chamber is compressed. 85

In testimony whereof I have hereunto subscribed my name.

HENRY ROMAN.
